UNITED STATES PATENT OFFICE

151,482

DESIGN FOR A WALLPAPER

Binnie B. Wilson, Chagrin Falls, Ohio

Application June 21, 1947, Serial No. 139,864

Term of patent 3½ years

(Cl. D59—10)

To all whom it may concern:

Be it known that I, Binnie B. Wilson, a citizen of the United States, residing at Chagrin Falls, in the county of Cuyahoga and State of Ohio, have invented a new, original, and ornamental Design for a Wallpaper, of which the following is a specification, reference being had to the accompanying drawing, forming part thereof.

The figure shows a plan view of a wallpaper showing my new design.

The broken lines indicate a design unit, which unit repeats vertically on the drawing as indicated.

I claim:

The ornamental design for a wallpaper, as shown and described.

BINNIE B. WILSON.
